Primary Examiner — Marissa J. Cash*Assistant Examiner* — Kayla Marie Bennett(74) *Attorney, Agent, or Firm* — Birchwood IP(57) **CLAIM**

The ornamental design for a curtain tieback, as shown and described.

DESCRIPTION

FIG. 1 is a front, top perspective view of a curtain tieback, showing my new design;

FIG. 2 is a rear, bottom perspective view thereof;

FIG. 3 is a front, top perspective view of the curtain tieback of FIG. 1 in a partially extended configuration.

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines show portions of the curtain tieback that form no part of the claimed design; The curtain tieback is shown in FIGS. 1-8 with symbolic break in its length. The dash-dot break lines and the appearance of any portion of within the break lines form no part of the claimed design.

1 Claim, 9 Drawing Sheets(56)
